UNITED STATES PATENT OFFICE.

EDWIN F. MATTASCH, OF ROSALIA, WASHINGTON.

PHONOGRAPH DIAPHRAGM.

Application filed May 22, 1922. Serial No. 562,723.

To all whom it may concern:

Be it known that I, EDWIN F. MATTASCH, a citizen of the United States, residing at Rosalia, in the county of Whitman and State 5 of Washington, have invented certain new and useful Improvements in Phonograph Diaphragms, of which the following is a specification.

My invention relates to the art of sound 10 recording and reproducing apparatus and more especially to vibratory diaphragms of the kind particularly employed in phonographs. It is an object of the invention to produce a diaphragm which will give softer 15 tones, uniformly distinct, regardless of the kind of material used in the horn and tone arm.

Again it is an object of the invention to 20 provide a diaphragm of a simple and effective construction that can be manufactured at minimum expense, of such material as will enable the diaphragm to respond effectively to sound vibrations without being 25 itself influenced by atmospheric changes.

25 The invention is illustrated in the accompanying drawing, in which:

Figure 1 is a face view of a diaphragm 30 embodying the invention.

Figure 2 is an edge view thereof.

Figure 3 is a magnified central cross section of the same.

In the drawing in which like numerals of reference indicate like parts in all of the figures, the diaphragm is shown composed of 35 a central disk 1 of silk impregnated with an elastic varnish such as is used on the wings of aeroplanes. To each side of the disk 1 is suitably secured (by cement for example) one or more thicknesses 2, 3 of a compound of wool, cotton and wood pulp, 40 such as a good quality of blotting paper for example, pressed to a thin edge in order to form a convexed center portion on each side of the disk 1. The center portion is of less diameter than the disk 1 so as to leave a flange by which the diaphragm can be 45 mounted in the sound box.

The needle holding arm of the sound box

(not shown) may be connected to the geometric center of the diaphragm in the usual 50 way.

After the parts 1, 2 and 3, etc., have been assembled and pressed tightly together, they are varnished over with an elastic waterproof varnish and when the same has dried, 55 the diaphragm is ready to be placed in the sound box of the phonograph.

It will be observed that my invention consists essentially of a disk of varnished silk, 60 to each side of which are suitably secured convexed disk-like bodies of lesser diameter than that of the silk disk and waterproofed by an elastic varnish.

I have found from experience that by the use of my invention, the tones produced are 65 softer and more uniformly distinct than with the types of diaphragms now in common use and enables the sound box employing my diaphragm to be used with any kind of a horn without diminishing the 70 advantageous features of the present invention.

I have also found that by the use of my improved diaphragm the harsh sounds and scratching noises usually produced are eliminated.

75 From the foregoing description, taken in connection with the accompanying drawings, it is thought the construction and advantages of my invention will be clear to those skilled in the art to which it appertains.

What I claim is:

A diaphragm composed of a varnished silk disk of uniform thickness throughout, a plurality of smaller disks of a compound 85 of wool, cotton and wood pulp, secured in superposed relation on each side of said silk disk and progressively decreasing in diameter from the silk disk outwardly, said smaller disks each having their edges 90 tapered to a knife edge whereby to provide convexed surfaces on each side of the silk disk, and elastic waterproof varnish coating over said disks.

EDWIN F. MATTASCH.
